CLAIM

The ornamental design for an archery bow stand, as shown and described.

DESCRIPTION

FIG. 1 is a front-right angled view of the archery bow stand;
 FIG. 2 is a front view thereof;
 FIG. 3 is a back view thereof;
 FIG. 4 is a right-side view thereof;
 FIG. 5 is a left-side view thereof;
 FIG. 6 is a top view thereof; and,
 FIG. 7 is a bottom view thereof.

The broken lines in the drawings depict unclaimed portions of the archery bow stand only and form no part of the claimed design.
